UNITED STATES PATENT OFFICE.

FRANCIS B. COCKBURN AND EDWARD S. BIRD, OF CINCINNATI, OHIO, ASSIGNEES TO THE LODGE & SHIPLEY MACHINE TOOL COMPANY, OF CINCINNATI, OHIO, A CORPORATION OF OHIO.

CRANK TURNER.

Application filed February 8, 1919. Serial No. 275,843.

To all whom it may concern:

Be it known that we, FRANCIS B. COCKBURN and EDWARD S. BIRD, subjects of Great Britain, and residing at Cincinnati, in the county of Hamilton and State of Ohio, have invented a new and useful Improvement in Crank Turners, of which the following specification is a full disclosure.

Our invention relates to a machine tool for turning crank shafts and more particularly it relates to a machine tool adapted for turning the crank pins thereof, which, in general practise, is a second step in the machining of a crank shaft subsequent to a first step of turning the center bearings and shaft ends in the standard type of lathe.

The object of the invention deals with the chucking of the work in various positions to center the crank pins to be turned, coincident to the axis of chuck rotation.

A further object is to provide a means for circumferentially clamping a bearing portion of the shaft and adjusting said means radially relative to the axis of chuck rotation to center a crank pin coincident to the axis of chuck rotation.

A further object is to provide an interchangeable gauge definitely determining the degree of radial adjustment.

Another object is to provide an extension chuck or adapter cooperating with the main chuck to extend the reach thereof.

A further object is to provide centering devices associated with the chucks adapted to engage a turned crank pin to radially position a crank pin to be turned coincident to the axis of chuck rotation.

A further object is to provide a rotatable chuck body having a throw-block clamping-ly engaging a bearing portion of a crank shaft and radially adjustable to position said shaft eccentric to the axis of chuck rotation to a degree coincident to the length of crank shaft throw, combined with means clamping an orbital portion of said shaft adjacent a crank pin to be turned, and adjustable transversely to the plane of the throw-block adjustment for centering a crank pin coincident to the axis of chuck rotation.

These and further objects dealing with the details of construction and arrangement of parts, contributing to the efficient operation and economic manufacture, will be fully understood by reference to the following

description and to the drawings, forming a part of this specification, of which:

Fig. 1 is a side elevation, partly broken and in section, of the right and left hand head-stocks and a portion of the lathe bed, showing the connecting spindle drive.

Fig. 2 is a side elevation of the chuck mechanism and a portion of each head-stock, showing a six-throw crank shaft with center bearings, chucked by turning the two outer crank pins.

Fig. 3 is a similar side elevation showing a six-throw crank shaft with center bearings, chucked for turning the second and fifth crank pins.

Fig. 4 is a side elevation, showing a six-throw crank shaft with center bearings, chucked for turning the two inner crank pins.

Fig. 5 is a top plan view of Fig. 4.

Fig. 6 is a side elevation showing a four-throw crank shaft with one center bearing, chucked for turning the two outer crank pins.

Fig. 7 is a side elevation showing a four-throw crank shaft with one center bearing, chucked for turning the two inner crank pins.

Fig. 8 is a side elevation showing a four-throw crank shaft with center bearings, chucked for turning the two outer crank pins.

Fig. 9 is a side elevation showing a four-throw crank shaft with center bearings, chucked for turning the two inner crank pins.

Fig. 10 is an enlarged transverse section on line 10, 10, Fig. 8.

Fig. 11 is an enlarged transverse section on line 11, 11, Fig. 9.

Fig. 12 is an enlarged transverse section on line 12, 12, Fig. 9.

Fig. 13 is an enlarged transverse section on line 13, 13, Fig. 3.

Fig. 14 is an enlarged transverse section on line 14, 14, Fig. 7.

Fig. 15 is an enlarged plan section on line 15, 15, Fig. 4.

The head-stocks 1 and 2 are of substantially duplicate construction, the left hand head-stock 1 being fixed to the lathe bed 3 and the right hand head-stock 2 being clamped thereto at desired locations.

The respective head-stock spindles 4, 5, are provided with drive gears 6, 7, meshing

70

75

80

85

90

95

100

105

110

with the intermediate gears 8, 9, journaled in brackets 10, 11, depending from each head-stock casing. The gears 8, 9, mesh with the sleeve pinion 12, 13, journaled in 5 the lower portions of said brackets and are restrained against lateral movement by the annular sleeve bosses 14, 15, and by the retaining collars 16 which are secured to the brackets. Both sleeve pinions 12, 13, are 10 splined to a transmission shaft 17 and the shaft is secured within the pinion 12 by a set screw 18, thereby preventing a lateral movement of said shaft. During a lateral 15 adjustment of the right hand head-stock, the sleeve pinion 13 slides upon the shaft 17. The main drive mechanism may be of any desired type, either direct or through suitable speed change mechanism engaging with the spindle gear 6 of the stationary head- 20 stock.

As the type of main drive has no direct bearing upon the present invention, no illustration or description thereof is herein presented.

25 The spindles 4, 5, are provided with flanges or chuck plates 20, 21, to which are secured the different chuck devices, as will now be described.

Main chucks.

30 The body portions of the right and left hand main chucks A and B are of similar design excepting as to length, one of them being longer than the other to accommodate 35 the long bearing end of a crank shaft to be turned. A second difference is that the chuck A is provided with a groove in its upper surface for the attachment of devices hereinafter described, it, of course, being 40 obvious that both the chuck bodies could be of equal length and both provided with said groove if desired.

The body portions of the chucks are of 45 hollow barrel formation (see Figs. 12, 13) and each are provided with a flange 22 for securing by bolts 23 to their respective spindle chuck plates 20, 21, of the right and left head-stocks. Each chuck is provided 50 with work engaging mechanism and as such mechanisms are, in the main, substantially alike, a description of one of them will suffice herein, except as to one detail, to be later described.

The vertical face of the chuck body is 55 provided with a groove or slide-way 25, in which is adjustably mounted a centering throw-block 26 rigidly secured in adjusted position by clamp bolts 27 extending through elongated slots in said throw-block 60 and screw threaded into the chuck body, (see Figs. 10, 11 and 15.). Seated in the upper surface of the throw-block 26 is a half bearing bush 28 secured thereto by a screw 29 and pivoted at 30 on the throw-block 26 is a 65 clamp arm 31, having a companion half-

bush 32 secured to said arm by a screw 33. The forward end of the clamp arm 31 is bifurcated for engagement with a clamp bolt and nut 34, 35, in a clamping operation, the bolt 34 being pivoted at 36 in a recess in 70 the throw-block.

As shown in Fig. 2, the bush 28 extends outwardly further than the upper bush 32 and is also provided with a pin 37 to relieve the screw 29 of end thrusts, the extended face of the bush 28 is engaged by the work, the bush acting as an abutment thrust member.

With the crank shaft bearing clamped on the throw-block 26, said block may be radially adjusted relative to the chuck body to bring the center of the adjacent crank pin to be turned, to the center of chuck rotation. This is accomplished by the following means:

Projecting laterally from the chuck body is a boss 40 and between this boss and the lower surface of the throw-block 26 is positioned a spacing sleeve or gauge 41, the three parts being clamped together by a clamp 90 screw 42 extending through said boss and sleeve and screw threaded into the throw-block. The sleeve 41 corresponds in length to the throw of the crank shaft being turned and is interchangeable with other spacing 95 sleeves of various lengths for definitely determining the adjustments of the throw-block 26 to accommodate crank shafts of different throw dimensions.

The throw-block 26 is provided with a U- 100 shaped laterally projecting flange 43 between the opposing sides of which one of the transverse arms of the chucked crank shaft projects. Screw threaded in the flange 43 at opposite points, we provide a pair of locating clamp screws 44, 45, adapted to engage the opposite sides of the crank shaft arms and adjustable to locate and clamp the crank shaft in position, with the center of the crank pin to be turned in coincident 110 alignment with the center of the chuck rotation.

The chucking operation is as follows:

Knowing the dimension of throw of the crank shaft to be turned, a spacing sleeve or gauge 41, of appropriate length, is selected, the clamp bolts 27 are loosened and the clamp screw 42 withdrawn to allow the spacing gauge, previously in use, to be replaced by a selected gauge. The clamp screw 42 is then replaced and tightened to clamp the gauge and throw-block rigidly to the boss 40. The clamp bolts 27 are then tightened, clamping the throw-block 26 firmly against the vertical face of the chuck body. After the throw-block is adjusted for a definite crank shaft throw the crank shaft is placed in position with a center bearing thereof resting upon the thrust bush 28 and the adjacent crank arm projecting radially be- 120 125 130

tween the locating clamp screws 44, 45. The clamp arm or strap 31 is swung to position and the clamp nut 35 slightly tightened to frictionally restrain the crank shaft against a free turning movement, if desired. In positioning the adjacent crank pin to be turned coincident with the axis of chuck rotation, the locating screw 45 is adjusted to center said crank pin and a lock nut 46 on said screw is tightened to lock the screw in set position. The clamp screw 44 is then tightened against the opposite side of the crank arm to rigidly secure the crank arm in adjusted position after which the clamp nut 35 is fully tightened to clamp the crank shaft bearing.

To provide for a wide range of throw-block adjustments, we provide an additional pair of tapped holes 47 in the U-shaped flange of said throw-block to accommodate the locating screws 44, 45, and for the same purpose, we provide an additional pair of tapped holes in the face of the chuck body to accommodate the clamp bolts 27.

In Fig. 2 the six-throw crank shaft with full center bearings is chucked for turning the two outer crank pins *a*, *f*, the end bearings 50, 50, being clamped to the throw-blocks of the right and left chucks A and B respectively.

Fig. 3 illustrates the method of chucking said six-throw shaft for turning the second and fifth crank pins *b* and *e*. In this case, an additional locating device is employed, (see Figs. 3 and 13). A groove or T-slot 55 is formed in the upper surface of the body of the chuck A and a bracket 56 is adjustably secured therein by a bolt 57 and nut 58. A locating V-head block 60 having a stud end 59 is adjustably mounted in the bracket 56 and is secured in adjusted position by a set screw 61. The locating block 60 is disposed at an angle of one hundred and twenty degrees (120°) from a radial line passing through the axes of the crank shaft and of chuck rotation and coincides with the angular disposition of the offset crank pins. With the crank shaft positioned, as shown in Fig. 3, the turned crank pin *a* is engaged by the V-head locating block 60 to accurately position said crank pin to the required one hundred and twenty degree (120°) angle to bring the crank pin *b* to proper turning position.

55 Extension chuck.

When turning the two inner crank pins *c* and *d* (see Fig. 4), extension chucks or adapters C and D are employed. These extension chucks extend the reach of the chuck mechanism to clamp the crank arms adjacent the crank pins to be turned. The clamping and centering mechanism of the chucks C and D is the same as that of the chucks A and B, as previously described,

the throw-blocks of the chucks A and B engaging the center bearings 52, 52, and the throw-blocks of the chucks C and D engaging the center bearings 51, 51. Each extension chuck is secured to the companion main 70 chuck by bolts 70. To accurately center the extension chuck upon the main chuck previous to tightening the bolts 70, we provide locating studs 71, 71, which extend through bushed orifices in the extension chuck flange 75 and into similar bushed orifices in the body portion of the main chuck. These locating studs are secured in position by set screws 72, 72, each engaging into a groove in said studs.

In Figs. 4 and 5 the crank pin *a* is turned one hundred and twenty degrees (120°) from the position shown in Figs. 3 and 13 and in consequence thereof the locating block 60 and bracket 56 will be turned to the opposite position from that shown in Figs. 3 and 13.

In Figs. 8, 9, 12, the four-throw crank shaft with full center bearings is shown in two chucked positions for turning, first, the crank pins *g* and *j*, and second, the crank pins *h* and *i*, in these cases only the main chucks A and B being employed. In the crank shaft shown, the crank pins are diametrically opposite, therefore a different locating block is provided comprising the V-head 75 adjustably clamped on a stud 76 of a bracket 77 by a set screw 78, said bracket being adjustably clamped in position in the T-slot 55 of the chuck body A by the bolt 79 and nut 80.

100

Auxiliary centering chucks.

Figs. 6 and 7 illustrate a four-throw crank shaft with one center bearing chucked in two turning positions. As shown, two short 105 main chucks are employed, but it is obvious that if the shaft end were longer, a longer main chuck body, such as chuck A, would be utilized. For the first turning operation of turning the end crank pins *h* and *n*, the shaft 110 is chucked the same as previously explained in connection with the six-throw shaft shown in Fig. 2. For chucking the shaft for turning the inner crank pins *l* and *m*, we employ auxiliary centering chucks E and F. Chucks 115 E, F, each comprise the body portion 90, which is attached to the adjacent chuck member by bolts 91 and locating studs 92, of the same construction as those used in attaching the chucks C D to the chucks A and B. The outer end of each body portion 90 is of U-formation (see Fig. 14) providing opposing walls in which are screw threaded a pair of locating bolts 93, 94, each adapted to engage one side of a crank arm to clamp the shaft against rocking. The upper surface of the chuck body 90, of the chuck E, is provided with a T-slot 95, in which is adjustably clamped a bracket 96 supporting a locating block 97, similar in construction 120

125

130

and function to the locating block 75, previously described. The block 97 engages the turned crank pin *k* to definitely locate the crank pin *l* coincident with the center of the 5 chuck rotation. If desired, the auxiliary chuck *F* may also be provided with a locating block to engage the turned crank pin *n*.

Having described the invention, we claim:

1. A crank-shaft chuck comprising a body 10 attachable to the face plate and constituting an axial elongation of the spindle unsupported at its outer end, work positioning and receiving mechanism on the end face of said body comprising a radially adjustable member, means on said radially adjustable member for circumferentially gripping a bearing portion of the shaft, a crank shaft throw length gauge sleeve on the body and forming a seat for the radially adjustable member, 15 means passing through said sleeve for radially clamping together said body, gauge and radially adjustable member, and means on the radially adjustable member for clamping a portion of the work holding it rigid 20 upon the axis of rotation.

2. A chuck for a crank shaft turner comprising a body portion, having one face adapted for secured to a spindle face plate, and the outer face on the unsupported end 30 of said body having crank shaft securing mechanism, comprising a member radially adjustable on the outer face, and having means for gripping a bearing portion of the crank shaft relative to the axis of rotation, 35 a removable gauge against which said radially adjustable member seats, determining a definite regulation thereof coincident to the crank shaft throw length, means for radially clamping the adjustable member and removable member to said body portion, means on said radially adjustable member for circumferentially clamping an adjacent crank shaft bearing and a chuck secured upon the outer 40 face of said body portion providing an ex- 45 tension section therefor for supplementarily clamping a crank shaft.

3. A crank-shaft chuck comprising a main chuck body and an extension chuck body removably secured thereto, each chuck body 50 having associated therewith a work-securing mechanism comprising a radially adjustable member clampingly embracing a bearing portion of a crank shaft, a removable gauge defining the degree of radial adjustment 55 coincident to the length of crank shaft throw, and means for clamping the radially adjustable member in adjusted position, a centering device on the main chuck body engaging a crank pin for centering another crank pin 60 coincident to the axis of chuck rotation, and means on the extension chuck body engaging a predetermined portion of the work.

4. A crank-shaft chuck comprising a main chuck body and an auxiliary chuck body removably secured thereto, a work-securing 65

mechanism carried by the main chuck body, and comprising a radially adjustable shaft engaging and clamping member, a removable gauge member providing a positive regulation of adjustment of the clamping member coincident to the length of crank shaft throw, means for securing the clamping member in an adjusted position, a centering device adjustable on the auxiliary chuck body and adapted to engage a crank pin to 70 center an adjacent crank pin coincident to the axis of chuck rotation, and means gripping a portion of the work adjacent to the crank pin to be turned.

5. A crank shaft chuck comprising a body 80 attachable to the spindle to constitute an axial elongation thereof unsupported at its outer end, work securing means on the end face of the body comprising a radially adjustable member, a removable gauge block corresponding in length to a predetermined throw of a crank shaft, means for radially clamping together relatively the said chuck body, gauge and radially adjustable member, said radially adjustable member comprising first, means for laterally clamping 90 an element of the crank shaft, holding it rigidly centered at the axis of rotation, and second, means for circumferentially clamping one of the crank shaft journals adjacent 95 the centered element.

6. A crank shaft chuck comprising a body attachable to the spindle to constitute an axial elongation thereof unsupported at its outer end, work securing means on the end face of the body comprising a radially adjustable member, a removable gauge block corresponding in length to a predetermined throw of a crank shaft, means for radially clamping together relatively the said chuck body, gauge and radially adjustable member, said radially adjustable member comprising first, means for laterally clamping 100 an element of the crank shaft, holding it rigidly centered at the axis of rotation, and second, means for circumferentially clamping one of the crank shaft journals adjacent 105 the centered element, and means attachable to an intermediate portion of the chuck body for the second operation, adapted to support 110 and position the first turned crank shaft bearing in rear of said circumferential clamping means.

7. A crank shaft chuck comprising a body attachable to the spindle to constitute an axial elongation thereof unsupported at its outer end, work securing means on the end face of the body comprising a radially adjustable member, a removable gauge block corresponding in length to a predetermined throw of a crank shaft, means for radially clamping together relatively the said chuck body, gauge and radially adjustable member, said radially adjustable member comprising first, means for laterally clamping an ele- 115 120 125 130

ment of the crank shaft, holding it rigidly centered at the axis of rotation, and second, means for circumferentially clamping one of the crank shaft journals adjacent the centered element, means attachable to an intermediate portion of the chuck body for the second operation, adapted to support and position the first turned crank shaft bearing in rear of said circumferential clamping means, a supplemental chuck body for a third operation, substantially a duplicate of the first-named chuck, and means extensibly clamping said second chuck body on the end face of the first chuck body while the crank shaft remains substantially as initially secured, the clamping members on the end face of the second chuck body correspondingly positioning and supporting an intermediate portion of the crank shaft appropriate to the third operation.

8. A crank shaft chuck attachable to the spindle and constituting an axial elongation thereof, work positioning and supporting members on the unsupported end face of said body comprising, a radially adjustable member, a removable gauge corresponding in length to a predetermined crank shaft throw, means for radially and relatively clamping said body gauge, and adjustable member, said adjustable member comprising first, means for laterally clamping an element of the crank shaft to hold it rigidly centered at the axis of rotation, second, means for circumferentially clamping an adjacent member of the crank shaft, a supplemental chuck body, and means for exten-

sibly clamping said second body on the end face of the first chuck while the crank shaft is in position, for chucking another portion of the crank shaft.

40

9. A crank shaft chuck comprising a body attachable to the spindle to constitute an axial elongation thereof unsupported at its outer end, work receiving means on the end face of the body comprising a radially adjustable member, a removable gauge block corresponding in length to a predetermined throw of the crank shaft, means for radially clamping together relatively the said chuck body, gauge and radially adjustable member, and a second chuck member removably mounted on the outer end of said body as an extension thereof, having crank shaft clamping and centering devices.

45

10. A crank shaft chucking and centering device, for a metal turning machine, comprising a body member, having plane faces at its opposite ends for coaxially uniting complementary body members and for mounting the same upon a spindle of a metal turning machine, and radially adjustable crank shaft clamping means mounted within one end of said body member.
